FLUID LOADER

William F. Schaezly, Louisville, Ky.

Application August 24, 1953, Serial No. 376,013

12 Claims. (Cl. 137—276)

This invention relates to fluid loaders, and more particularly to loaders equipped with counterbalances for balancing the filling pipe at all angles of adjustment.

Loaders of the general type to which the invention relates have been in use for some time, and have been used extensively in loading petroleum products. Such loaders usually consist of a standpipe having a swing joint at its top to which is attached a horizontal pipe having a depending filler pipe at its outer end. Many loaders are equipped with weight counterbalances to balance the horizontal and filler pipes in various positions of adjustment. The weight type counterbalances have not been sufficiently delicate in their operation to properly balance the device in all positions of adjustment, and usually they are designed to hold the device in substantially vertical inoperative position. This resulted in the operator having to hold the horizontal pipe in its overhanging delivery position.

The object of the present invention is to provide a loader of this general type in which the weight of the delivery end of the device is compensated for in all positions of adjustment.

A further object of the invention is to provide compensating mechanism associated with the swing joint to form a unit, wherein the mounting of the compensating mechanism will permit free and normal movement of the swing joint about its several axes.

Another object is the provision of compensating mechanism which is adjustable for variations in weight load.

Other objects of the invention will become apparent from the following description of practical embodiments thereof, when taken in conjunction with the drawings which accompany, and form a part of, this specification.

in the drawings:

Figure 1 is a perspective view of the upper portion of a loader embodying the principles of the present invention;

Figure 2 is an enlarged fragmentary side view of the swing joint and compensating unit and associated parts;

Figure 3 is a further enlarged vertical section, through that portion of the device shown in Figure 2, and is taken on the line 3—3 of Figure 2;

Figure 4 is a horizontal section taken on the line 4—4 of Figure 3 on the horizontal axis of the swing joint;

Figure 5 is a horizontal section taken on the line 5—5 of Figure 3;

Figure 6 is a vertical section at right angles to Figure 3, and is taken on the line 6—6 of Figure 3; and,

Figure 7 is a sectional view through one buffer of the compensating mechanism showing a modified form.

Figure 8 is a vertical sectional view through a modified form of swing joint and compensating unit and associated parts; and,

Figure 9 is a side view of the structure shown in Fig. 8.

Referring to the invention in detail, the loader comprises a standpipe 1 having a swing joint 2 fixed to its upper end, and a delivery pipe secured to the swing joint,

which may be a single length of pipe 3 or a telescoping sleeve to which is attached the open-ended filler pipe 4. The filler pipe is shown as having a universal coupling with the pipe 3, at 5. Compensating, or counterbalancing, mechanism 6 is carried by the swing joint 2. This disclosure is concerned primarily with the swing joint and compensating mechanism.

The swing joint is designed to provide both horizontal and vertical swinging movement for the delivery pipe. The swing joint consists of three major elements, the straight section 7, the S-shaped casting 8, and the S-shaped casting 9.

The straight section 7 forms a vertical pivot to permit the delivery pipe to be moved in a horizontal plane. It is provided with a bushing 10 at its lower end, threaded externally as at 11, for attachment to the upper end of the standpipe 1. Above the threads 11, the bushing is peripherally grooved to form a ball bearing race 12. A tubular casting 13 having its lower end reduced to form a shoulder 14 fits within the bushing with the shoulder 14 resting upon the ball bearings 15 in the raceway 12. This forms a thrust bearing to take the weight of the superimposed structure and permit the casting 13 to rotate freely with respect to the bushing 10. Bushing 10 has an upstanding collar 16 which is spaced from, and surrounds, the lower portion of casting 13 to form a stuffing box. The usual packing 17, follower 18 and gland nut 19 are provided to provide a seal to prevent leakage. The bushing is exteriorly threaded to receive the threaded lower end of a cage 20. The upper end of the cage is threaded to receive a bearing retainer 21 which seats upon ball bearings 22 in a raceway 23 formed upon an annular flange 24 projecting from the casting 13. By means of this structure, two spaced bearings are provided for the casting to ensure it being held firmly in position and yet permit easy rotation.

The upper end of casting 13 is threaded into the lower end of S-shaped casting 8. The two members are drawn into tight engagement so that they function as a single unit. Thus, when casting 8 is turned in a horizontal plane, the straight, vertical section 7 will be caused to rotate in its bearings. Due to the S shape of casting 8, the axis of its upper end lies in a horizontal plane. A bushing 25 is threaded into the upper end of casting 8 and forms a journal in which a thimble 26 threaded into, and projecting from, the end of S-shaped casting 9 is seated for rotative movement. Bushing 25 has a projecting annular collar surrounding, and spaced from, the thimble 26 to form a stuffing box. Packing 27, follower 28 and gland nut 29 are used to provide a liquid-tight seal between the bushing and thimble. Due to the shape of casting 9, the outer end of the casting will have its axis in the plane of the axis of vertical casting 7 in all positions of adjustment of casting 9. Delivery pipe 3 has its end threaded into the outer end of casting 9.

From the above description it will be obvious that the delivery pipe may be moved in a horizontal arc by the rotation of the vertical casting 7 in its bearings, and in a vertical direction by reason of the swivel connection between the castings 8 and 9. This provides universal movement for the delivery pipe.

By special construction, the weight load is removed from the swivel joint between castings 8 and 9, and means are provided adapted to be mounted directly upon the swing joint assembly mechanism for counterbalancing the weight of the delivery pipe and to compensate for the varying weight load upon progressively increasing or decreasing the overhang of the delivery pipe in use. For this purpose, the castings 8 and 9 have outwardly projecting bosses which serve as trunnions and are journaled in bearings supported from the castings. In other words, a boss projecting from one casting is journaled in

a bearing supported by the other casting. Casting 8 has a boss 30 projecting from its side with its axis coincident with the axis of the horizontal swivel joint between the castings 8 and 9. The end of the boss is of reduced diameter and fits within an anti-friction bearing 31 which is threaded into a circular opening in the end of a bracket 32 projecting from the casting 9. Casting 9 has a similar boss 33 whose axis is coincident with that of the swivel joint, working in the bearing 34 threaded in an opening in a bracket 35 extending from casting 8. The load of the delivery pipe, therefore, is transferred from the casting 9 through bracket 32 and the boss 30 to casting 8, and through boss 33 and bracket 35 to casting 8, thus relieving the swivel connection between the castings.

The counterbalancing and compensating mechanism is carried directly by the castings 8 and 9. The mechanism is divided into two similar units on opposite sides of the swing joint for balance and to prevent torque, and portions of the mechanism serve to hold the castings 8 and 9 in assembled relation. Each of the compensating units comprises a hydraulic buffer 36 and a bell-crank lever 37 connected by flexible means, such as the chains 38.

Each buffer consists of a cylinder 39 which contains a piston 40 and a compression spring 41. A cylinder head 42 closes the bottom of the cylinder, and a head 43 closes the top. The spring 41 has its ends bearing against piston 40 and head 43. Upward movement of the piston serves to compress the spring. The piston has the usual rod 44 which passes through an opening in the head 43 and has its outer end connected to one end of chain 38. A bellows 45 surrounds the opening in head 43 and the piston rod to prevent leakage of the hydraulic fluid within the cylinder. The bellows is sufficiently flexible to allow some sidewise movement to compensate for side draft upon the piston rod caused by the bell-crank 37 following an arcuate path of movement. Piston 40 is provided with ports 46 to permit flow of fluid past the piston as the piston moves upwardly within the cylinder. A flap valve 47 closes the ports as the piston moves downwardly. Head 43 is formed integrally with a bracket 48 which projects outwardly from the lower portion of casting 8. There is a bracket for each buffer 36, arranged to hold the buffers symmetrically positioned on either side of the swing joint. The lower ends of the buffers are joined by means of a tie bar 49.

The bell-cranks 37 are connected to the casting 9 to move with it. Each bell-crank is fastened to the casting by two cap screws 50 and 51. The screws pass through one arm 52 of the bell-cranks so that the axis of rotation of the bell-cranks will be the same as that of the casting 9. The cap screws 50 and 51 attaching the bell-crank 37 shown at the left in Figure 3 are threaded in the bracket 32 projecting from casting 9, and cap screws 50 and 51 attaching bell-crank 37 at the right of Figure 3 are threaded respectively into a boss 53 formed on casting 9 and into the boss 33 which forms the trunnion on which casting 9 rotates. By this arrangement, the bell-cranks are drawn up close against the brackets 32 and 35 and overlie the ends of the bosses 30 and 33, thereby preventing endwise movement of the bosses in their respective bearings and securing the castings 8 and 9 in assembled relation.

The second arm 54 of each of the bell-cranks is connected to one of the chains 38 to couple each bell-crank to its respective buffer so that rotative movement of casting 9 about its connection with casting 8 will cause relative movement of the pistons in the buffers to counterbalance the delivery pipe in its changed position. Arms 34 are bifurcated so that the chain coupling means may be received between the two arm positions. The chains have draw buckles 56 at their upper ends, each having an adjustable pivot block 57 slidably mounted within it and held in positions of adjustment by means of an adjustment screw 58. Pivot block 57 is provided with an opening 59

to receive a pin 60 which also passes through openings 61 in the bifurcated arms 54. Openings 61 are arranged in two rows 62 and 63 which diverge radially from the pivotal points of the bell-cranks. By placing the pin 60 in selected ones of the openings 61 different degrees of tension may be obtained in the buffers. After the pin 60 is positioned, fine adjustment may be made by means of the screw 58.

In Figure 7 a buffer having a mechanical, rather than a hydraulic mechanism is shown. This differs from the buffer previously described only in the substitution of a solid piston head 64 for the hydraulic head 40. A similar spring 41 is used within the cylinder 39. Air within the cylinder serves to retard, or slow up, piston action in much the same manner as the fluid in the hydraulic buffer previously described.

The present loader is designed to be positioned vertically and the delivery pipe will be substantially vertical when not in use. When a tank, tank car, truck, or the like is to be loaded the delivery pipe is pulled down to a substantially horizontal position. It will be obvious that this causes the casting 9 to pivot about its connection with casting 8, rocking the bell-cranks to raise their arms 54. This raises the pistons in the buffer cylinders and compresses springs 41. The increasing compression of the springs will compensate for the progressively increasing overhang of the delivery pipe. If the compression of the springs was at a uniform rate, the torque of the loader would increase to the point that it would be difficult to pull the delivery pipe to horizontal position. It will be noted, however, that bell-crank arms 54 move on an arc and the increased spring compression will not be at a uniform rate. This will enable the delivery pipe to be pulled down into horizontal position with little effort, yet the springs are sufficiently compressed to lift the delivery pipe to vertical inoperative position when the pressure upon the pipe is released. It will also be noted that all parts of the compensating mechanism are carried by the units of the swing joint, so that no strain is placed upon the standpipe or delivery pipe. The swing joint and compensating mechanism become a unitary assembly, with the bell-cranks serving to hold the swing joint in assembled position.

In Figures 8 and 9 there is shown a modified form of swing joint and compensating mechanism. In most respects, the structure is the same as that previously described, and the changes are made primarily to provide a structure which is more practical with heavier loads and longer delivery pipes, and particularly with telescoping delivery pipes. The modified structure permits the use of longer crank arms on the compensating mechanism to balance heavier loads. The changes principally concern the lower straight section of the swing joint and the mounting of the buffer cylinders.

The upper S-shaped section 65 has its horizontal terminal portion swivelly connected to the horizontal terminal portion of the intermediate S-shaped section 66 as before. The lower vertical section 67 and cage 68 are reversed. The lower vertical section is externally threaded at its lower end to screw into the top of the standpipe; and has an annular flange 69 between its ends to seat a bearing race 70. An internal flange 71 on cage 68 bears against the opposite side of bearing race 70 and a second bearing race 72 is positioned against the opposite side of flange 71. A jamb nut 73 threads on the vertical section 67 and bears against bearing race 72 to lock the bearing assembly in place. The upper end of the cage is internally threaded to receive a union 74 which is threaded to receive the nipple 75 screwed into the vertical terminal portion of the intermediate S-shaped section 66. Union 74 has a downward extension 76 terminating closely adjacent the top of the lower vertical section 67 and is of the same diameter as the lower section. The outer walls of the downward extension and the top of the lower section are peripherally

grooved to receive sealing rings 77. A seal ring 78 bridges the space between the downward extension and the lower vertical section and covers the sealing rings to make a fluid-tight connection between the two elements.

In this form of the invention the buffer cylinders 79 are provided with the top and bottom cylinder heads, as in the previous form, and these heads are held upon the cylinder ends by means of tie rods. In this form, however, a bracket 80 having a central opening is slipped over the cylinder to a position midway between its ends and short tie rods 81 are provided which pass through openings in the top and bottom cylinder heads and are threaded into the bracket 80. Horizontal extensions 82 on the brackets 80 are bored to receive the ends of a shaft 83 which is journaled in a boss 84 formed on the rear of the cage 63. The ends of the shaft are peripherally grooved, as at 85, and set screws 86 threaded in the brackets 80 seat in the grooves to lock the cylinders into position upon the cage. This mounting will permit the cylinders to rock slightly as the bell-cranks 87 through the chain connection 88 draw up the pistons in the cylinders. This will provide a straight line pull at all times and gradually reduce the friction upon the piston rod.

The bell-cranks 67 are provided with set screws 89 which may be adjusted to contact chains 88 when the delivery pipe is pulled down and the upper S-shaped section of the swing joint rocked about its pivot. Usually the screws will be so adjusted that they will contact the chains and push them outward, thus effectively shortening their lengths to further compress the springs in the buffers just as the delivery pipe reaches horizontal position. This will compensate for the extra load imposed when the telescopic sections of the delivery pipe are extended.

While in the above practical embodiments of the invention have been disclosed, it will be evident that the structure described and illustrated is merely by way of example, and changes may be made from the precise details disclosed without departing from the scope of the appended claims.

What is claimed is:

1. A load compensating swing joint for fluid loaders comprising, a lower vertical section, an S-shaped intermediate section having one vertical and one horizontal terminal portion with the vertical terminal portion swivelly connected to the top of the lower vertical section whereby said intermediate section may rotate with respect to the lower section about a vertical axis, an S-shaped upper section having one horizontal and one vertical terminal portion with the horizontal terminal portion swivelly connected to the horizontal terminal portion of the intermediate section whereby said upper section may rotate with respect to the intermediate section about a horizontal axis, a pair of buffer elements one mounted vertically on each side of said intermediate section with the vertical plane of the buffers being substantially parallel to a vertical plane passing through the horizontal axis of rotation between said upper and intermediate joint sections, a pair of actuating arms carried by said upper section with one on each side of said upper section and extending perpendicularly to the horizontal axis of rotation of said upper section, and flexible means connecting the free ends of said arms and said buffers.

2. In a load compensating swing joint for fluid loaders as claimed in claim 1, means for adjusting the lengths of said connecting means to vary the strength of said buffers.

3. In a load compensating swing joint for fluid loaders as claimed in claim 1, each of said buffers comprising a cylinder, top and bottom cylinder heads, a piston in the cylinder, a piston rod connected to the piston and projecting through the top cylinder head for attachment to

said connecting means, and a coiled spring positioned between said piston and the top cylinder head.

4. In a load compensating swing joint for fluid loaders as claimed in claim 2, means to adjust the length of said connecting means to vary the initial compression of said springs, and said arms having a plurality of openings spaced along their lengths to provide attachment for said connecting means whereby the effective length of said arms may be varied.

5. A load compensating swing joint for fluid loaders comprising, a lower straight vertical section, an S-shaped intermediate section having one vertical and one horizontal terminal portion with the vertical terminal portion swivelly connected upon the upper end of the lower section whereby said intermediate section may rotate relative to the lower section about a vertical axis, an S-shaped upper section having one horizontal and one vertical terminal portion with the horizontal portion swivelly connected to the horizontal terminal portion of the intermediate section whereby said upper section may rotate relative to the intermediate section about a horizontal axis, a trunnion on each of said intermediate and upper sections projecting outwardly in opposite directions coaxially with the axis of rotation between said upper and intermediate sections, a bracket projecting from each of said upper and intermediate sections in which the trunnions of the other of said upper and intermediate sections is journaled, bell cranks having one arm connected to said upper section and extending across the axis of rotation between said upper and intermediate sections and over the ends of said trunnions to prevent endwise movement of said trunnions in said brackets, said bell cranks each having another arm projecting perpendicularly to the axis of rotation between said upper and intermediate sections, a pair of buffer elements one mounted vertically on each side of said intermediate section with the vertical plane of the buffers being substantially parallel to a vertical plane passing through the horizontal axis of rotation between the upper and intermediate sections, and flexible means connecting the free arms of said bell cranks and said buffers.

6. In a load compensating swing joint for fluid loaders as claimed in claim 5, means for adjusting the lengths of said connecting means to vary the strength of said buffers.

7. In a load compensating swing joint for fluid loaders as claimed in claim 5, each of said buffers comprising a cylinder, top and bottom cylinder heads, a piston in the cylinder, a piston rod connected to the piston and projecting through the top cylinder head for attachment to said connecting means, and a coiled spring positioned between said piston and the top cylinder head.

8. In a load compensating swing joint for fluid loaders as claimed in claim 7, means to adjust the lengths of said connecting means to vary the initial compression of said springs, and said free arms of said bell cranks being bifurcated to receive said connecting portions between the resulting pairs of arms, said pairs of arms having a plurality of openings spaced along their lengths whereby attachment to said connecting means to vary the effective lengths of said free arms.

9. In a load compensating swing joint for fluid loaders as claimed in claim 8, the means for adjusting the lengths of the connecting means comprising a drawbuckle connected to said connecting means, a block movable in said drawbuckle and attachable to the free arms of said bell cranks, and means to move said block.

10. A load compensating swing joint for fluid loaders comprising, a lower vertical section, an S-shaped intermediate section having one vertical and one horizontal terminal portion, a downwardly extending cage carried by the vertical terminal portion of the intermediate section surrounding and swivelly mounted upon the lower vertical section whereby said intermediate section and cage may rotate with respect to the lower section about

at vertical axis, an S-shaped upper section having one horizontal and one vertical terminal portion with the horizontal terminal portion swivelly connected to the horizontal terminal portion of the intermediate section whereby said upper section may rotate with respect to the intermediate section about a horizontal axis, a pair of buffer elements one pivotally mounted on each side of the cage, a pair of actuating arms carried by said upper section one on each side thereof and extending perpendicularly to the horizontal axis of rotation of said upper section, and flexible means connecting the free ends of said arms and said buffers.

11. In a load compensating swing joint for fluid loaders as claimed in claim 10, each of said buffers comprising a cylinder, top and bottom cylinder heads, a piston in the cylinder, a piston rod in the cylinder and projecting through the top cylinder head for attachment to said connecting means, and a coiled spring positioned be-
